UNITED STATES PATENT OFFICE.

GEORGE F. FISHER, OF NORTH TONAWANDA, NEW YORK.

BUILDING-BLOCK.

SPECIFICATION forming part of Letters Patent No. 781,413, dated January 31, 1905.

Application filed September 14, 1904. Serial No. 224,381.

To all whom it may concern:

Be it known that I, GEORGE F. FISHER, a citizen of the United States, residing at North Tonawanda, in the county of Niagara and State 5 of New York, have invented certain new and useful Improvements in Building-Blocks, of which the following is a specification.

My invention relates to improvements in building-blocks, and more particularly to hollow building-blocks.

The objects of my invention are to construct a hollow building-block that can be molded in a molding-press; to provide a hollow building-block with inclosed sides and ends, which 15 prevents the circulation of air through the wall; to provide a hollow block which by reason of its construction receives a full bearing from the blocks directly beneath and provides a full bearing for the block directly 20 above, while also giving the mortar at the ends of the block full bearing.

Further objects are to provide a separable hollow block which permits of completely closing the sides and end and to form the two 25 sections in different sizes, which permits of reversing the blocks in the successive rows or courses, which permits of breaking joints, thus forming a perfect bond.

To these ends the invention consists in forming a hollow block in two sections, one narrower than the other, and in forming each section with opposing open sides which form a complete hollow block having its sides and ends closed.

30 In the drawings, Figure 1 is a sectional perspective view of a wall constructed of blocks embodying my invention. Fig. 2 is a perspective view of one part of my improved building-block. Fig. 3 is a perspective view 40 of the other part of my block.

Referring now to the drawings in detail, like letters of reference refer to like parts in the several figures.

The reference-letter A designates the blocks, 45 each comprising two parts B C, the part C being narrower than the part B to bring the longitudinal seam to one side of the longitudinal vertical center of the wall. Each part of the block is made hollow and comprises an 50 outer wall D, a top wall E, a bottom wall F,

and end walls G, thus leaving the inner opposing sides open, with the edges of the top, bottom, and end walls of both parts held in contact with each other. This forms a hollow building-block with its sides and ends 55 closed. The part C may be maintained at a certain size irrespective of the thickness of the wall, while the part B may be made wider to provide the increased thickness desired. In a wall twelve inches thick the narrow part C 60 may be three inches wide and as long as desired, while the wide part is molded to a width of nine inches and to a length corresponding with the length of the narrow part. In the construction of a wall sixteen inches thick the 65 narrow part C need not be increased in width, while the wide part may be molded to a width of thirteen inches. It is therefore apparent that it is only necessary to increase the width of the wide part of the block when a wall of 70 increased thickness is desired.

When the blocks are molded to a length of twelve inches or more, I provide transverse strengthening-ribs H, and for convenience in setting the wide part I provide hand-holes I, 75 which permit of conveniently grasping and placing the same in proper position.

The walls of the blocks I preferably mold to a thickness of one and one-half inches, which leaves a slight depression K in the narrow part and a chamber L in the wide part.

The blocks are reversed in alternate courses to bring the narrow parts thereof in one course between the wide parts of the blocks in the courses above and below, thus breaking joints 85 and forming a solid structure.

With the sides and the ends of the blocks closed, inclosed, and unconnected dead-air chambers are provided within the blocks, which prevent the circulation of air through 90 the wall and render the house warmer in winter and cooler in summer. This construction of block also forms a solid bed for the binding mortar and assures a more perfect bond than possible to attain with hollow blocks now 95 in use.

Having thus described my invention, what I claim is—

1. A hollow building-block formed in two parts, one part being wider than the other, and 100

both parts having depressions in their opposing sides.

2. A hollow building-block formed in two parts, one part being wider than the other, and 5 both parts being of equal length and chambered from their meeting faces outward.

3. In a building, a wall formed of hollow blocks, each block formed of two chambered parts of unequal width, the blocks being reversed in alternate courses to bring the nar-

row part thereof between two wide parts, thus breaking joints.

In testimony whereof I have affixed my signature in the presence of two subscribing witnesses.

GEORGE F. FISHER.
